United States Patent

Des. 234,563

Patented Mar. 25, 1975

234,563

PORTRABLE EASEL

Marion K. Williams, 800 1st Drive NW. 205,
Austin, Minn. 55912

Filed Mar. 7, 1973, Ser. No. 339,386

Term of patent 14 years

Int. Cl. D6—04

U.S. Cl. D6—188

FIG. 1 is a front and right side perspective view of a portable easel showing my new design;

FIG. 2 is a front elevational view;

FIG. 3 is a top plan view;

FIG. 4 is a left side elevational view, the right side being essentially a mirror image thereof; and

FIG. 5 is a rear elevational view.

I claim:

The ornamental design for a portable easel, as shown and described.
